UNITED STATES PATENT OFFICE.

FRANK C. STEWART, OF SPRINGFIELD, MISSOURI.

ANTIFROST DEVICE.

1,394,648.

Specification of Letters Patent. Patented Oct. 25, 1921.

Application filed October 25, 1920. Serial No. 419,340.

To all whom it may concern:

Be it known that I, FRANK C. STEWART, a citizen of the United States, residing at Springfield, in the county of Greene and 5 State of Missouri, have invented certain new and useful Improvements in Antifrost Devices, of which the following is a specification.

This invention relates to attachments for 10 the wind shields of motor vehicles, street cars, the lookout windows of pilot houses of ships, the windows of locomotive cabs and the like and the primary object of the invention is to provide an improved means 15 for effectively preventing the accumulation of moisture, frost, snow and the like on lookout windows and windshields, so that the possibility of accidents occurring by the obscuring of the driver's vision is reduced 20 to a minimum.

Another object of the invention is to provide an improved means for heating the windows of lookouts and the like so as to prevent the accumulating of moisture, snow 25 or the like thereon, said means being out of the line of vision of the driver or pilot, so that the interference with the driver's or pilot's sight is prevented.

A further object of the invention is to 30 provide means for heating the windows of lookouts and the like which comprises a hood arranged adjacent to the top of the window and one or more heating elements having means arranged thereon for concentrating 35 and directing the heat generated thereby on the window, said heat concentrating and directing means being adjustable so that the desired volume of heat may be directed toward the window.

40 A still further object of the invention is to provide a device of this character, which is applicable for windows and windshields of all types of devices, which is of simple and durable construction, one that is simple 45 and easy to manufacture, and one which can be placed upon the market at a reasonable cost.

With these and other objects in view, the 50 invention consists in the novel construction, arrangement and formation of parts as will be hereinafter more specifically described, claimed and illustrated throughout the accompanying drawings, forming a part of this specification, in which drawings:

55 Figure 1 is a perspective view of the im- 110

proved lookout window heater showing the same applied to the motorman's window of a street car.

Fig. 2 is a vertical longitudinal section through the same. 60

Fig. 3 is an end elevation of the same.

Fig. 4 is a detail transverse section through the same.

Fig. 5 is a detail vertical transverse section through the improved heater showing 65 the same applied to a car window, illustrating a slightly modified form of the invention.

Referring to the drawings in detail, wherein similar reference characters designate corresponding parts throughout the several views, the letter A indicates a street car, and B the improved anti-frost device or heater for the lookout window C of the car. 70

The street car A is of the ordinary or any 75 preferred construction and has been shown merely for illustrating the use of the improved device B and it is to be understood that the device is to be used wherever practical, and as shown the street car A includes 80 the frame 10 for the lookout window C.

The frame 10 is of the ordinary or any preferred construction.

The improved anti frost heating device B 85 includes a hood 15 which is of substantially semi-cylindrical formation and is provided at its terminals with end walls 16. The end walls 16 are provided with depending substantially triangular shaped supporting arms or brackets 17 and these brackets or 90 arms 17 are in turn provided with right angularly extending attaching flanges 18 which may be bolted or otherwise secured as at 19 to the frame 10. The hood 15 is arranged at the upper edge of the window C 95 so as to be out of the line of the driver's or motorman's vision, and is so arranged as to direct or throw the heat rays generated by means which will be hereinafter more fully described, toward the lookout window 100 C. The end walls 16 of the hood 15 are provided with suitable alined bearings 20, which rotatably receive the longitudinally extending hollow shaft 21. This shaft receives the line wires 22 for the heaters, which 105 will be hereinafter more fully described. The heaters are designated by the numeral 23 and each includes a plug 24 formed of suitable insulation around which is coiled

a suitable resistance wire 25, of any pre- 110

ferred make generally utilized in electric heaters. The plugs 24 are threaded in suitable sockets which may be carried by the reflectors 26 or by the shaft 21. The reflectors 26 are of substantially saucer shape and have sleeves 27 secured thereto at their outer faces for receiving the shaft 21. These sleeves 27 are held on the shaft 21 against accidental movement by means of thumb screws or the like 28.

While two heaters have been shown, it is to be understood that more than two can be utilized if so desired on windows having a relatively great width or only one on windows of relatively small width, such as the lookout windows of locomotives or the like. The reflectors 26 are of such a construction as to concentrate the heat rays and direct the same downward on the look out window C, and a means 30 has been provided for adjusting the position of the reflectors and heater 23 so that the amount of heat directed toward the window can be controlled.

The adjusting means 30 for the heaters 23 includes a lever 31 which is pivotally mounted intermediate its ends on one end of the shaft 21 which is provided with a yoke 32 for the reception of the same. The upper end of the lever 31 is provided with a right angular foot 33, the inner end of which is adapted to seat in any one of a plurality of equi-distantly spaced openings 34 formed in the side wall 16. The end of the lever 31 opposite to the angled end 33 thereof is provided with a handle 35 so as to permit the ready manipulation of the same. In order to normally hold the foot 33 in engagement with one of the openings 34, an expansion coil spring 36 is provided. The inner end 40 of this expansion coil spring 36 rests upon a radially extending foot 37 which is formed integral with or secured to the shaft 21 in any preferred manner. The outer end of the spring 36 is secured to the lever 31 in any preferred manner. It thus can be seen that the angled foot 33 is normally urged toward the end wall 16 so that the same may be held against accidental displacement from one of the openings 34.

In operation of the improved device, it is merely necessary to depress the handle end 35 of the lever 31 to move the foot 33 from out of the opening 34 in which it is seated and then swing the lever so as to rotate the shaft 21 in bearings 20. When the reflectors 26 and the heaters reach their desired position, the handle 35 is released and the spring 36 will urge the foot 33 into engagement with one of the openings. The line wires 22 are extended to any suitable source of electrical energy and may be provided with the usual hand operated switch so that the heaters can be turned on or off if so desired.

In order to prevent contacting of the persons in the car with the heater, a plurality

of arcuate guard fingers 40 are provided. As shown these guard fingers 40 extend below the heaters 23 and have their terminals secured to suitable longitudinally extending rods 41. These rods 41 in turn are connected respectively to the supporting brackets 17 and the forward ends of the side walls 16. These side walls 16, if so desired, may be provided with orifices 42 so as to permit the escape of heat therefrom.

As shown in Fig. 5 of the drawing, the hood 15 may be provided with a lining 45, but this lining is not essential and has only been provided to form an air space between the heaters and the wall of the hood.

As stated, the hood 15 is arranged at the upper edge of the window and above the head of the driver of the car so as to be out of line of his vision and is so shaped as to direct the rays of heat toward the window C. The reflectors 26 also concentrate the heat and direct the same toward the window and it can be seen that the window will become thoroughly heated and thus prevent the adhering of moisture, snow or the like thereon. This forms an efficient and durable means for preventing the obscuring of the driver's vision and thus accidents from this cause will be eliminated.

It is also to be understood that the heaters may be of strength or size according to the nature of the lookout with which the device is to be associated.

Changes in details may be made without departing from the spirit or scope of this invention; but,

I claim:

1. The combination with a transparent body, of an anti-frost device therefor comprising a transversely extending arcuate hood arranged at the upper edge of the body, heaters arranged in the hood, reflectors carried by the heaters, spaced guard fingers carried by the hood and arranged in front of the heaters, and means for swinging the heaters and reflectors so as to adjust the position thereof in relation to the body.

2. The combination with a transparent body, of an anti-frost device therefor comprising a transversely extending semi-cylindrical hood arranged at the upper edge of the body, depending supporting brackets carried by the terminals of the hood, means for securing the brackets at opposite sides of the transparent body, electric heaters arranged in the hood, reflectors carried by the electric heaters, and means for adjusting the position of said electric heaters in relation to the body.

3. As a new article of manufacture, an anti-frost device for windows comprising a substantially cylindrical hood, attaching brackets carried by the terminals of the hood, a longitudinally extending shaft ar

ranged for rotation within the hood, electric heaters carried by the shaft, and means for rotating the shaft.

4. As a new article of manufacture, an anti-frost device for windows comprising a hood, a longitudinally extending shaft arranged in the hood for rotation, electric heaters carried by the shaft, means for rotating the shaft, and means for locking the shaft against rotation and in any preferred position.

5. As a new article of manufacture, an anti-frost device comprising a substantially semi-cylindrical hood, end walls formed on the hood, depending triangularly shaped attaching brackets formed on the end walls, bearings carried by the end walls, a hollow shaft rotatably mounted in said bearings, electric heaters carried by the shaft, line wires disposed in said hollow shaft and electrically connected to said heaters, a lever for rotating said shaft, and means for holding the lever against movement.

6. As a new article of manufacture, an anti-frost device for windows comprising a substantially semi-cylindrical hood, end walls formed on the hood, depending triangularly shaped supporting brackets formed on the end walls, bearings carried by the end walls, a shaft of hollow formation rotatably mounted in said bearings, sleeves secured to said shaft, reflectors carried by said sleeves, electric heaters arranged centrally within said reflectors, line wires disposed in said hollow shaft and electrically connected to said heaters, a lever pivotally mounted intermediate its ends upon the shaft, a right angularly disposed foot formed on one end of the lever, one of the end walls of the hood having a plurality of spaced openings formed therein arranged to receive the foot, and spring means for normally urging the foot into engagement with any one of said openings.

FRANK C. STEWART.
